UNITED STATES PATENT OFFICE.

JOHN E. LEAVITT, OF BOSTON, MASSACHUSETTS, ASSIGNOR OF ONE-HALF
TO EDWIN G. CARLETON, OF MALDEN, MASSACHUSETTS.

DETACHABLE WAISTBAND.

SPECIFICATION forming part of Letters Patent No. 578,294, dated March 2, 1897.

Application filed April 22, 1893. Serial No. 471,372. (No model.)

To all whom it may concern:

Be it known that I, JOHN E. LEAVITT, residing in Boston, in the county of Suffolk and State of Massachusetts, have invented an Improvement in Detachable Waistbands, of which the following description, in connection with the accompanying drawings, is a specification, like letters on the drawings representing like parts.

5 This invention relates to detachable bands for shirt-waists, blouses, and like garments and is especially adapted to be used by children to support the trousers, skirts, and like articles of wearing-apparel.

10 My present invention has for its object to provide a waist, blouse, or like article with a waistband, of a construction as will be described, which will afford a greater freedom of movement to the body of the wearer and 20 will relieve the wearer from strain when the body is bent or inclined forward.

15 In accordance with my invention the waistband for the whole or a portion of its length is made of elastic material and is detachably secured for the whole or a portion of its 25 length to the outside of the waist, blouse, or other like article, or it may be a belt or band encircling the body of the wearer, the said band being provided with buttons or other 30 suitable fastening devices, to which the trousers, skirts, or other wearing-apparel may be secured to hold the same on the body of the wearer.

35 The particular features of my invention will be pointed out in the claim at the end of this specification.

Figure 1 represents a small boy standing in an upright position and provided with a waistband embodying my invention. Fig. 2 represents 40 a sufficient portion of the body of the boy shown in Fig. 1 as bent forward to illustrate the working of this invention. Fig. 3 is a developed view of a portion of the shirt-waist shown in Fig. 1 to more clearly show the 45 construction of band preferred by me; Fig. 4, an inner side view of substantially one-half of the band shown in Fig. 3; Fig. 5, a sectional detail, on an enlarged scale, to be referred to, the section being taken on the line 50 55, Fig. 3, looking toward the right; and Fig. 6, a perspective view, on an enlarged scale, of

one form of device by which the band is secured to the outside of the waist.

In the present instance I have chosen to illustrate my invention as applied to the shirt-waist ⁵⁵ *a* of a boy provided with trousers *a'*.

In accordance with my invention the shirt-waist *a* has detachably secured to it a waistband composed in whole or in part of elastic material. The waistband referred to is herein shown (see Fig. 3) as composed of three parts *a² a³ a⁴*, the part *a³* being made of elastic material, such as an elastic webbing, cord, or tape, and the parts *a² a⁴* being preferably made of elastic material, but they may be 65 made of non-elastic material.

In accordance with my invention the elastic portion *a³* of the band, which in practice is designed to lie at the back of the wearer, is detachably secured to the waist *a* on the outside thereof, and as one means by which this result may be accomplished I may employ the fastening device shown separately in Fig. 6, it consisting of a hollow or tubular portion *a⁶*, provided with ears *a⁷ a⁸*, forming bearings for 70 a spring rod or pintle having its ends *a⁹ a¹⁰* turned in opposite directions and engaging arms *a¹² a¹³* loosely mounted on the said spring rod or pintle. The arms *a¹² a¹³* are adapted to be turned up into a substantially vertical 80 position, that is, substantially at right angles to the tubular portion, so as to permit the said arms to be inserted through a suitable hole or opening *a¹⁵* in the waist, as shown in Figs. 3 and 4, to detachably secure the said 85 fastening device to the outside of the waist *a*.

The elastic rear portion *a³* of the band is designed to be inserted through the tubular portion of the fastening and to slide or move freely therethrough, for a purpose as will be 90 described, and between adjacent fastening devices the said elastic band has secured to it in any suitable or desired manner a button *b* or other suitable device for engagement with the rear portion of the trousers *a'*.

95 The parts *a² a⁴* are subjected to less strain than the rear portion *a³*, and therefore, if desired, the said parts *a² a⁴* may be secured on the inner side of the waist *a* by means of buttons *b²*, or other suitable devices, extended 100 through suitable buttonholes *b³*, the part *a²* being herein represented as provided with

two buttons b^2 and the part a^4 with three buttons.

When the parts $a^2 a^4$ of the band are located on the inner side of the waist a , as herein shown, they may be detachably secured to the elastic rear portion a^3 , preferably on the inner side of the waist a , by inserting the opposite ends of the rear portion a^3 of the band through suitable eyelets or holes $b^5 b^6$ and joining the ends of the said rear portion to the free end of the parts $a^2 a^4$, which may be accomplished by hooks b^7 , attached to the free ends of the parts $a^2 a^4$, engaging eyes b^8 , attached to the ends of the rear portion a^3 of the band, as clearly illustrated in Fig. 5.

The trousers a' , as herein shown, are secured on the body of the boy by the buttons $b b^2$, which engage suitable buttonholes in the waistband attached to the trousers, and in the normal or upright position shown in Fig. 1 the waistband of the trousers covers the waistband a , but when the body of the boy is bent forward, as represented in Fig. 2, the rear portion or back of the shirt-waist is elevated, while the rear portion of the trousers is not elevated, but remains practically stationary, owing to the elasticity of the rear portion a^3 of the band, which gives or elongates with the forward movement of the body. The elastic rear portion a^3 slides in the tubular portion of the detachable fastenings, and the sliding movement of the said elastic rear portion is limited by stops, shown as enlargements c at the opposite ends of the said elastic rear portion, which enlargements may be made by knotting the cord or band, or they may be metallic or other pieces fastened to the said band, the said enlargements being larger than the diameter or opening of the tubular portion a^6 and preventing the cord or band a^3 from being further drawn through the tubular portions of the extreme or endmost detachable fastenings.

By the construction of elastic band herein described the seat of the trousers retains its original fullness, thereby permitting the body to bend or move forward freely and unhampered and without subjecting the trousers to

strain. Furthermore, by means of the elastic connection or rear portion of the band between the outside of the waist a and the trousers the boy is relieved from compression or cutting action of the band at the front of the body.

When the elastic portion a^3 has been moved so as to bring the stops c into engagement with the endmost detachable fastenings, as described, the portions of the elastic band between the said stops and the nearest front buttons (marked 2 3 in Fig. 3) are elongated, and the slight strain upon the band is transmitted to the said side buttons, which, being located at the side of the body, does not hurt or inconvenience the wearer.

I do not desire to limit my invention to the use of a shirt-waist, blouse, or like garment, for the elastic band may be detachably fastened to the outside of a belt, and for the purpose of the claim I shall designate these different wearing articles as a "waist-body."

When it is desired to wash the waist-body, the band, when constructed as herein shown, may be detached from the waist-body by disconnecting the parts $a^2 a^4$ from the part a^3 and removing the buttons b^2 from their buttonholes and next unclamping the detachable fastenings by turning the spring-arms $a^{12} a^{13}$ up into a position substantially at right angles to that shown in Fig. 6 and withdrawing the said arms from their holes a^{15} .

I claim—

The combination with a waist-body, of a band consisting of the parts $a^2 a^4$ secured on the inside of the waist-body, and the elastic portion a^3 detachably secured to the waist-body on the outside of the same, and connections joining the ends of the elastic portion a^3 to the parts $a^2 a^4$, substantially as described.

In testimony whereof I have signed my name to this specification in the presence of two subscribing witnesses.

JOHN E. LEAVITT.
